United States Patent Office

Des. 184,087
Patented Dec. 16, 1958

184,087

PLATE OR SIMILAR ARTICLE

Alfred Dube, Lincoln, Ill., assignor to Stetson China Co.,
Lincoln, Ill., a corporation of Illinois

Application August 4, 1958, Serial No. 52,026

Term of patent 14 years

(Cl. D44—15)

The figure is a top plan view of a plate of conventional configuration showing my new design.

I claim:

The ornamental design for a plate or similar article, as shown and described.
